UNITED STATES PATENT OFFICE.

JOSEPH FERGUSON, OF PHILADELPHIA, PENNSYLVANIA, ASSIGNOR TO
STEAD & MILLER, OF SAME PLACE.

DESIGN FOR A CURTAIN.

SPECIFICATION forming part of Design No. 17,981, dated December 27, 1887.

Application filed November 22, 1887. Serial No. 256,360. Term of patent 3½ years.

To all whom it may concern:

Be it known that I, JOSEPH FERGUSON, a citizen of the United States, residing at Philadelphia, in the county of Philadelphia and State of Pennsylvania, have invented and produced a new and original Design for a Chenille Curtain, of which the following is a specification, reference being had to the accompanying photographic print, forming a part thereof, which conveys to any one skilled in the art a clear understanding of the same, and

is sufficient to enable such person to use my invention.

What I claim as my invention, and desire to secure by Letters Patent, is—

The design for a chenille curtain, consisting of the ornamentalations shown in the photographic print accompanying this specification.

JOSEPH FERGUSON.
